UNITED STATES PATENT OFFICE.

CARL J. BAER, OF RIVERSIDE, ILLINOIS.

BOAT-PROPELLING MEANS.

Application filed November 17, 1919. Serial No. 338,591.

To all whom it may concern:

Be it known that I, CARL J. BAER, a citizen of the United States, residing at Riverside, in the county of Cook and State of Illinois, have invented certain new and useful Improvements in Boat-Propelling Means, of which the following is a specification.

My invention relates to improvements in means for propelling or forcing boats through the water and has for its object the provision of improved means of this character, capable of propelling or moving boats through the water with great efficiency, and with a minimum resistance to the lift of the propelling elements out of the water. Other objects will appear hereinafter. The invention consists in the combinations and arrangements of boats hereinafter described and claimed.

The invention will be best understood by reference to the accompanying drawings, forming a part of this specification and in which:

Fig. 1 is a top plan view of a boat equipped with propelling means embodying the invention.

Fig. 2. A side view of the same.

Fig. 3. An enlarged detail plan view of a portion of one of two flexible endless chain propellers employed in the construction.

Fig. 4. A section taken on line 4—4 of Fig. 3.

Fig. 5. An enlarged plan view of a portion of a modified form of construction of propelling means.

Fig. 6. Section taken on line 6—6 of Fig. 5.

Fig. 7. Section taken on line 7—7 of Fig. 5.

The form of construction illustrated in Figs. 1, 2, 3 and 4 comprises a boat body, 8, of any usual or desirable construction having propelling wheels or sprockets, 9, arranged on opposite sides thereof, said wheels being driven by suitable power contained within the boat (not shown). The wheels, 9, are arranged in pairs on opposite sides of the boat, 8, and flexible endless chain propellers or driving elements are arranged to operate over each pair of said wheels, the lower or rearwardly traveling portion of each propelling element being immersed in the water through which the boat travels. Each of the propelling elements consists of a plurality of substantially rectangular compartments, 10, preferably of sheet metal, and having per-

forated lugs or ears at their ends pivotally connected by means of pivot pins, 11, into an endless flexible chain, traveling over the sprocket wheels, 9, as shown. Each of the compartments 10, is divided by a horizontal partition, 12, of cork or other buoyant material and the side walls of each compartment, both above and below the partition, 12, are provided with perforations, 13, permitting of the free escape of air therefrom and also of the limited passage of water therethrough. By this arrangement a very effective driving engagement with the water is effected. The compartments are left entirely open at both top and bottom to permit of free entry of water thereto. The use of the compartments in an endless chain, as described, causes each compartment to be presented to the water at an angle, as will be understood. The water immediately rushes into the compartment, expelling the air through the perforations 13 and, by the time the compartment reaches a position approximately parallel with the water line, it is completely filled with water. Theoretically at least, the compartments which are filled with water have a combined inertia which is practically equal to the resistance encountered by the boat in its passage through the water. The net result is that the compartments have no relative movement with respect to the water, but merely push the boat forward therethrough. As the compartments are lifted out of the water they are of course tilted, as shown in Fig. 2, and the water is automatically evacuated from the compartments in the same manner that they are automatically filled.

By this means, the propelling elements will remain, during operation, substantially stationary with reference to the water in which they engage, their operation being substantially similar to that of the chain tractor elements on a land tractor, affording ample reaction for forcing the boat forward. The limited passage of the water through the perforations in the walls of the compartment tend to create friction thereon, thus adding to the tractive force available.

In the modified form of construction illustrated in Figs. 5, 6 and 7, the compartments, 14, constituting the different members of the endless chain propellers are made of considerable depth and substantially closed at the top, although perforations, 13, are provided in the walls and top thereof,

for the free passage of air and the limited passage of water.

The forward and rear walls of compartments, 14, are covered first by a lining of 5 foraminated material, such as burlap, 15, and which is reinforced with a lining of a woven wire mesh material, 16, such arrangement tending to greatly increase the resistance offered to the bodily movement of the compartments with reference to the water in 10 which they operate and thus increasing their tractive, or moving force. Otherwise, the construction is the same as that already described.

15 While I have illustrated and described the preferred forms of construction for carrying my invention into effect, these are capable of variation and modification without departing from the spirit of the invention. I, therefore, do not wish to be limited to the precise details of construction set forth, but desire to avail myself of such variations and modifications as come within the scope of the appended claims.

20 25 Having thus fully described my invention what I claim as new and desire to secure by Letters Patent is:

1. A propelling element comprising a chambered structure provided with walls of foraminated material, permitting the unobstructed passage of air and water in either direction.

2. A propelling element comprising a chambered structure provided with apertured walls, permitting the unobstructed passage of air and water in either direction.

3. The combination with a boat, of propelling means therefor comprising endless flexible elements arranged to travel longitudinally thereof, said elements being provided with water engaging members of foraminated material, permitting the unobstructed passage of air and water in either direction.

4. Propelling means for boats comprising chambered elements provided with perforated walls permitting free passage of air, and instrumentalities adapted to successively present said elements to the water at an angle, whereby the chambers thereof may be automatically filled with water, and to withdraw said elements from the water at an angle, whereby to automatically discharge the water from said chambers, substantially as described.

5. Propelling means for boats comprising a plurality of chambered elements provided with perforated walls permitting free passage of air, and having a combined water capacity such that the inertia of the filled chambers, when immersed in water, is substantially equal to the resistance offered to the passage of the boat through the water, and means for automatically filling said chambers as the elements are presented to the water, and for automatically emptying the chambers as the elements are withdrawn from the water, substantially as described.

CARL J. BAER.
